UNITED STATES PATENT OFFICE.

ARTHUR NEWHAM, OF VICTORIA, BRITISH COLUMBIA, CANADA, ASSIGNOR TO
CANADIAN VINCENT VALVE COMPANY LIMITED, OF VICTORIA, BRITISH
COLUMBIA, CANADA.

VALVE.

1,281,814.

Specification of Letters Patent. Patented Oct. 15, 1918.

Application filed March 14, 1918. Serial No. 222,368.

To all whom it may concern:

Be it known that I, ARTHUR NEWHAM, a subject of the King of Great Britain, residing at 1019 Southgate street, in the city 5 of Victoria, Province of British Columbia, Dominion of Canada, have invented certain new and useful Improvements in Valves, of which the following is a specification.

This invention relates to improvements 10 in relief valves, with particular reference to those used in steam engine cylinders for the opening and closing of the drain pipes of such cylinders, and the object of the invention is to provide a valve of this character 15 which is adapted to be maintained, under normal conditions of operation, in the drain-pipe closing position by the pressure of the steam in the steam chest or main but which, when acted upon by an abnormal 20 increase of pressure within the cylinder due to water therein, will automatically overcome the steam pressure holding it closed, and open so that the water may be discharged through the drain pipe and the 25 normal pressure relieved, thus effectually preventing accident to the machinery arising from such a cause.

The invention consists essentially of the improved construction hereinafter described 30 in detail in the accompanying specification and drawings.

In the drawings:

Figure 1 is a side elevation of an embodiment of the invention.

Fig. 2 is a cross sectional view.

Fig. 3 is a cross sectional view taken at right angles, Fig. 2.

Fig. 4 is a plan view.

Fig. 5 shows a section of a modified form 40 of the invention, the section being taken transversely through the inlet port.

In the drawings like characters of reference indicate corresponding parts in each figure.

45 Referring to the drawings, A represents the casing having aligned inlet and outlet ports 10 and 11 having screw threaded engagement with conduits 12 and 13 which lead respectively to the engine cylinder and 50 to the drainer or condenser. The pipe 12 may be formed of several branches or a plurality of ports 10 may be provided by which a number of cylinders may be connected to the casing at the same time. The ports 10 55 and 11 connect respectively with ports 14

and 15, formed by dividing the interior of the casing by an intercepting partition or web 16, the ports being of the shape shown in Fig. 2, being separated by the partition 16^a, and being controlled by a reciprocable disk valve 17 normally held open by a spring 18 which presses against the stem 19, the stem reciprocating in a cylindrical guide-way 20 forming part of the casing, the tension of the spring being conveniently adjusted by a set screw 21 extending through the casing and abutting a follower plate 22 at the end of the spring.

In its open position the valve 17 is designed to abut projecting lugs 23 on a cap 24 which closes an aperture or port 25 in the casing. The cap is itself formed with a port or opening 26 to which a pipe 27 is connected which leads to the steam chest or other part of the engine 75 which is supplied with steam when the engine is operating. The valve 17 is designed to reciprocate in a cylindrical extension 28 and by-pass ports 29 and 30 are formed at the side of the cylindrical extension permitting the steam chest to drain around the valve when open.

To provide for the removal of dirt and scales from the interior of the casing, drainage ports 31 and 32 may be provided, normally closed by set screws 33 and 34. The top of the cap may be formed with a hexagonal nut 35 by which the same may be screwed on and unscrewed.

In operation, when the steam is off, the 90 ports will be as shown in Fig. 2, when both the engine and the steam chest may drain through the casing to the drain pipe 13, thus permitting the water condensation to drain off. When the steam is on, the valve 95 17 is seated under its pressure closing the ports 14 and 15 and cutting off communication between the cylinder and the drain and also between the steam chest and the drain.

On an abnormal increase of pressure taking place in the cylinder due to water therein being compressed between the piston and the end of the cylinder, the water will be forced down the drain pipe 12 into ports 10 and 14 and, being intercepted by the partition 16, will be directed with its full force on that area of the valve face 17 which extends above the partition and, as the total pressure per square inch on the valve on its drain-pipe side will then be greater than the 105 110

total pressure on its steam side, it will readily be seen that the steam pressure holding the valve closed will be overcome so that it will be opened by the water pressure, thus allowing the water to escape through ports 15 and 11 so that the abnormal pressure is relieved before it can effect any damage, when the valve will again be closed by the normal steam pressure.

10 In the modified form of the invention shown in Fig. 5 the compartment D is divided into a plurality of compartments separated by secondary webs or partitions 16^a and 16^c extending from the main web to 15 the walls of the valve casing and each of these secondary compartments thus formed would have a connection or inlet port 10^a, 10^b, 10^c, and in this way a number of cylinders would be connected to one valve.

20 Each of these secondary webs 16^b and 16^c would form a valve seat so that when the valve was closed they would all be closed and not only separated from the lower compartment but from each other.

25 As many changes could be made in the above construction and many apparently widely different embodiments of my invention, within the scope of the claims, constructed without departing from the spirit 30 or scope thereof, it is intended that all matter contained in the accompanying specifications and drawings shall be interpreted as illustrative and not in a limiting sense.

What I claim as my invention is:

35 1. A drain valve comprising a casing having two alined ports, inlet and outlet respectively, said casing being provided with a partition dividing its interior into two parts connected respectively to the afore 40 said ports, a cylindrical extension on the casing leading from the partition, a valve adapted to reciprocate in the cylindrical extension having a valve stem, said valve being normally closable on the edge of said 45 partition by steam pressure on its steam side, and operable to overcome said pressure by excess water pressure on its opposite side, a cylindrical guide-way for the valve stem,

a compression spring in the guide-way, an adjusting screw extending through the casing, a follower between the adjusting screw and the compression spring, a cap adapted to normally close the cylindrical extension, formed with projections engaging the valve, and a steam pipe connected to the cap. 50 55

2. A drain valve comprising a casing having two alined ports, inlet and outlet respectively, said casing being provided with a partition dividing its interior into two parts connected respectively to the aforesaid ports, a cylindrical extension on the casing leading from the partition, a valve adapted to reciprocate in the cylindrical extension having a valve stem, said valve being normally closable on the edge of said partition 60 by steam pressure on its steam side and operable to overcome said pressure by excess water pressure on its opposite side, a cylindrical guide-way for the valve stem, a compression spring in the guide-way, an 65 adjusting screw extending through the casing, a follower between the adjusting screw and the compression spring, a cap adapted to normally close the cylindrical extension formed with projections engaging the valve, 70 a steam pipe connected to the cap, a drainage port in the cylindrical extension and a set screw opening and closing the port. 75

3. A drain valve comprising a valve casing having inlet and outlet drain openings 80 and a steam inlet opening, an intercepting partition within said casing, the said partition dividing the interior of the casing into two chambers of unequal size and its edge forming a valve seat, a valve mounted 85 for reciprocating within said casing and adapted to seat under steam pressure, on the edge of the partition to close communication between the said chambers, projections engaging the valve in its outward 90 movement, and spring means for unseating the valve when the steam pressure is relieved.

Dated at Victoria, B. C., March, 1918.

ARTHUR NEWHAM.
